CLAIM

The ornamental design for telephone set with moveable display, as shown and described.

DESCRIPTION

FIG. 1 is a top plan view of a telephone set with moveable display, showing our new design;

FIG. 2 is a front elevational view thereof;

FIG. 3 is a bottom plan view thereof;

FIG. 4 is a rear elevational view thereof;

FIG. 5 is a side elevational view thereof taken from the right side of FIG. 1;

FIG. 6 is a side elevational view thereof taken from the left side of FIG. 1;

FIG. 7 is a perspective view thereof;

FIG. 8 is a perspective view thereof with the handset removed; and

FIG. 9 is a side elevational view thereof with the display set flat.
